UNITED STATES PATENT OFFICE.

FÉLIX EMILE VALOIS, OF HAVERHILL, MASSACHUSETTS, ASSIGNOR TO HAMEL SHOE MACHINERY COMPANY, A CORPORATION OF MASSACHUSETTS.

SHOE MACHINE.

1,425,558.

Specification of Letters Patent. Patented Aug. 15, 1922.

Application filed December 7, 1917. Serial No. 205,918.

To all whom it may concern:

Be it known that FÉLIX E. VALOIS, a citizen of the United States, residing at Haverhill, in the county of Essex and State of Massachusetts, has invented certain new and useful Improvements in Shoe Machines, of which the following is a specification, reference being had therein to the accompanying drawings.

10 This invention relates to shoe machines and more specifically to a device herein termed a "Baltimore attachment" for use upon rough rounders or outersole stitching machines, said device being arranged automatically to provide for varying the width of projection of the shoe sole or of the line of stitching, respectively, beyond the upper in producing what is termed in the trade a "Baltimore" effect.

20 While mechanisms have heretofore been devised for producing the above effect in the machines mentioned, so far as is known, all such mechanisms were so intimately associated with the general machine structure 25 as to preclude any possibility of applying them to existing machines unprovided therewith.

It is an object therefore of the present invention to devise an attachment readily applicable to existing forms of either the outersole stitcher or the rough rounding machine, which can be applied or removed at pleasure without disturbing the operative relationship of the machine parts and which, when 35 in operation, shall automatically vary the distance of the line of stitches or of the edge of the sole respectively from the upper of the shoe, and which shall cause said variation to be in accordance with a fixed and 40 predetermined pattern.

It is a further object of the invention to provide interchangeable pattern means whereby the automatic action of the attachment may be varied for use with different 45 classes of work.

It is a further object to provide a pattern-member of material which may be easily shaped by the operator according to the requirements of individual lots of shoes, thus 50 avoiding loss of time and the maintenance of an extensive assortment of slightly varying pattern-members.

It is a further object of the invention to provide a device of the above character suitable for use upon either right or left shoes.

It is a further object to so construct such an attachment as to avoid complexity of parts with its attendant high cost of production and upkeep while at the same time securing all the above noted advantages in 60 operation.

Other and further objects and advantages of the invention together with improved details of construction and desirable combinations of parts will be hereinafter described and specifically pointed out in the claims, reference being had to the annexed drawings for an illustration of a preferred embodiment of the invention wherein:

Fig. 1 is a side elevation of a rough rounder machine of usual type showing the invention applied thereto, certain of the elements of the rough rounder mechanism being omitted for clearness of illustration.

Fig. 2 is a perspective, from the right 75 hand side, of the automatic regulating attachment forming the subject matter of this invention.

Fig. 3 is a perspective of one of the interchangeable pattern-members employed with 80 the attachment.

The machine herein illustrated is a rough rounding machine of well known form, and as the present invention is not concerned with the main operative elements of this 85 machine, it will be unnecessary to describe such parts at length.

1 is a standard or support upon which is mounted the machine head 2 in the usual manner. At 3 is indicated the main drive 90 shaft, having fixed thereto an eccentric 4, adapted to operate, through the eccentric strap 5 and the rod 6, intermediate connections not herein illustrated to reciprocate the cutting knives, all in usual and well 95 known manner.

7 is the manually retractable presser foot and at 8 is a relatively fixed work guide carried upon the supporting bracket 9 forming a part of, or being attached to, the machine 100 head. At 10 is a member carried upon the forward portion of the bracket 9, having formed in the front face thereof a channel 11, acting as a guide for the vertically adjustable auxiliary work guide or gauge 12. 105 Vertically slidable within a suitable opening formed in the bracket 9 is a supporting rod 13, normally held in raised position by a suitable spring, not shown, this rod having pivoted thereto at the point 14 a lever-mem- 110

ber 15, said lever-member projecting forwardly of its pivot at 16, and having pivotally mounted upon its forward end at 17 the guide-member 12. The guide-member 12 at 5 the point 18 projects above its pivotal support and engaging with said end 18 is a spring-member 19, acting to throw the lower portion of the guide-member 12 rearwardly and into engagement with the bottom of the 10 channel-member 11.

Pivoted at 20 upon a portion of the head is a lever arm 21, said lever arm having its forward end at 22 arranged to engage with the upper end of the rod 13. At 23 is indicated a rod adjustably secured at 24 to the lever 21 and extending downwardly to a convenient point for control by the operator as for example, by means of a treadle, although it is understood that other devices 15 under control of the operator might well be substituted for such treadle means. At 25 is indicated a bracket adapted for attachment to the machine head as by means of bolts 26 and 27 passing through suitably 20 formed openings 28, 28^a provided in said bracket, and engaging in corresponding openings in the machine head. The bracket-member 25 as shown (Fig. 2) is formed with an open channel 29 in its upper surface, the 25 sides and bottom of said channel being suitably finished to form a guide-way for a reciprocable part to be described. Slidable along said channel 29 is a cam-carrier 30, said cam-carrier being channeled out 30 throughout its entire length whereby to form a trough-like structure, the channeled out portion 31 of said carrier forming a holder or receptacle for a removable or detachable pattern cam-member 32. Projecting across the cam-carrier at 33 are pins or 35 other suitable means adapted for rigidly positioning the pattern-member within the cam-carrier, it being noted that as herein shown the pattern-member is beveled off as 40 at 34 in such a manner as to engage beneath the rear pin 33 to thereby prevent movement of the pattern-member rearwardly with respect to the cam-carrier. 45 indicates a set screw projecting through the wall of the channel 29 and adapted to engage the 50 side of the cam-carrier 30 thereby to provide suitable frictioning means for preventing too great freedom of movement of the cam-carrier in its guiding channel.

55 Upon the rearward extremity of lever-member 15 is mounted a roller 37, said roller being so positioned as to engage the upper surface of the pattern cam-member 32 when the latter is properly positioned within the 60 cam-carrier. The pattern-member 32 as herein shown is in the form of a substantially flat plate fitting snugly within the channel 31 of the cam-carrier. While this pattern-member 32 may be formed of hardened steel for example, if desired, it is the 65

purpose of this invention to construct the pattern-member of relatively soft material, such for example as soft brass, lead, or fibre board. When so formed it is intended that the upper edge 40 thereof shall form the pattern cam-member which may thus be easily varied in configuration without necessitating the employment of machine tools,—a file or knife being all that is required for changing the contour of the cam surface. It is therefore possible by the employment of this device to provide for variations in the cam in accordance with slight changes in the style of shoes without necessitating the provision of a large and expensive assortment of pattern cams. 70 75 80

The opposite edges of the cam-carrier are provided upon their upper surfaces with series of rack-teeth 35, 36, said rack-teeth being adapted for engagement by a pair of 85 pawls to be hereinafter described.

Pivoted upon a projecting boss 41 of the bracket 25 is a lever 42, the upper end of said lever being formed with a head 43 located at a slight distance from the upper 90 surface of the cam-carrier 30. 44 is a pin fixed within said head 43 projecting outwardly above said cam-carrier and forming the pivotal support for a pawl-carrier 45. The pawl-carrier 45 as herein shown in provided with two pawls 46 and 47 fixed thereto and projecting in opposite directions, said 95 pawls lying respectively in the planes of the two racks 35 and 36. While as herein shown these pawls are integral with the 100 pawl-carrier, it is clearly evident that they might be formed as separate members and attached thereto, it being necessary, however, with the present construction that these pawls should bear a fixed relation to each 105 other.

While in the present disclosure the cam-carrier has been shown as provided with two separate spaced apart racks and the pawl-members as adapted to engage with the respective racks, it is within the scope of the present invention to employ a single rack-member with a pair of pawls lying in the plane thereof and adapted for alternative engagement with the same rack. 110 115

Pivoted in suitable lugs 48 projecting from the bracket 25 is a manually controllable lever 49, said lever being forked at its forward end to project on either side of the bracket 9 thus presenting portions upon 120 either side of the work guide for ready manipulation by the hand of the operator. The lever-member 49 projects rearwardly of its pivot at 50, and is adapted to have connected thereto one end of a coiled spring 51, the 125 opposite end of said spring being connected to a pin 52, projecting from the pawl 43, the specific point of connection, however, of this spring with the pawl being immaterial. The rearward extremity of the member 50 130

therefore reached substantially the lower limit of its movement.

Upon attainment of the desired width of the sole in producing the Baltimore effect, 5 the greatest width of projection being adjacent the shank, the treadle controlling the position of the lever 21 is released by the operator, thereby permitting the gauge 12 to rise to its uppermost position under action of 10 the spring-lifted rod 13, whereupon the edge gauge 8 acts, during the finishing of the shank, to guide the shoe. Upon presentation of the other shoe of a pair to the machine the shank is first formed upon that side of the 15 shoe upon which the Baltimore effect is to be produced and upon reaching the forepart of the shoe the treadle is again depressed, the roll 37 still resting upon the high part of cam 32 whereby the edge gauge 12 is suddenly moved down to its lowermost position 20 as shown in the drawing, thereby producing the extreme extension of the sole. The operator immediately lifts the lever 49 throwing pawl 47 out of action and throwing pawl 25 46 into engagement with rack 35 whereupon cam-carrier 30 is moved forwardly, the roll 37 traveling upon the upper face 40 of the cam-member 32 and permitting the gradual rise of the guide 12, until the roll reaches 30 and rests upon the rear end of the cam at which time pawl 46 reaches the end of rack 35 and further movement ceases, the guide 12 being thus held in position for production 35 of the normal extension of the forepart of the shoe. When the shank of the shoe is reached the treadle is released permitting the guide 12 to rise to its upper position the gauge 8 thereupon performing its function and the parts thus being restored to their initial 40 position.

It is clear that the application of this attachment comprising the auxiliary work guide or gauge 12 with its actuating arm and its position-controlling means comprising bracket 25 carrying the cam mechanism and the lever mechanism for moving it, in no way changes the operative relationship of the parts of the machine to which it is applied, but is merely superposed thereon. No 45 disturbance of these relationships or any dismantling of the machine is therefore necessary during its attachment or detachment.

While as herein shown the mechanism is applied to a rough rounder it is clearly evident that the same mechanism is adapted 50 for use in connection with other machines operating upon an edge of a shoe such for example as the outersole stitcher, in which it is desired to vary the distance of the line of stitching from the shoe upper. It is also evident that various changes and modifications 55 in the detail structure of this device may be made without departing from the essential features and mode of operation

thereof, and the invention is intended to include all such changes and modifications as well as such applications of the present structure to other machines as may fall within the scope of the annexed claims.

Having thus described the invention and a preferred embodiment thereof together with details of construction and the mode of operation of the same what I claim and desire to protect by Letters Patent of the United States is:—

1. An attachment for shoe machines comprising a bracket-member having guiding means thereon, a carrier movable along said guiding means, a pattern-cam mounted upon said carrier and mechanism for moving said carrier along said guiding means.

2. In a shoe machine, in combination an adjustable edge gauge and means for progressively adjusting the same, said means comprising a pattern cam-member movable in a rectilinear path and means constructed and arranged to advance or retract said pattern cam-member at the will of the operator.

3. An attachment for shoe machines comprising a bracket-member having a channel-like guideway formed therein, a carrier movable along said guideway, a pattern cam detachably supported upon said carrier and automatically actuated mechanism for moving said carrier along said guideway.

4. An attachment for shoe machines comprising a bracket-member having a channel-like guideway formed therein, a carrier movable along said guideway, said carrier having a slot therein, a pattern-cam adapted to be removably positioned within said slot, and means for reciprocating said carrier within said guideway.

5. In an attachment for shoe machines, in combination, a guide-member, a cam-carrier 105 slideable thereon, a pair of racks upon said carrier, and a pair of oppositely acting pawls constructed and arranged for alternate driving engagement with the respective racks.

6. In a shoe machine, in combination, a reciprocable cam-carrier having rack-teeth thereon, a pair of oppositely directed, vibratory pawls, means for alternately throwing said pawls into engagement with rack-teeth 115 of said carrier, a cam-member supported upon said carrier and means for vibrating said pawls.

7. In an attachment for shoe machines, in combination, a cam-carrier reciprocable in a 120 rectilinear path and having rack-teeth thereon, a vibratory lever, a pair of oppositely acting pawls carried thereby, and actuating means, comprising a resilient element, for throwing said pawls alternately into driving 125 engagement with the rack-teeth upon said carrier.

8. In a Baltimore attachment, in combina-

may be formed if desired as shown at 53 as an upwardly projecting pin adapted to constitute a guide or support for the coil of the spring 51, this, however, not being an 5 essential feature of the invention.

From the above described construction it will be evident that upon lifting the forward end of the lever 49 from the position shown in Fig. 1, the coil spring 51 will be 10 expanded and will thereby pull down upon the pawl 46, causing the pawl carrier to turn upon its pivot, lifting the pawl 47 from engagement with the rack 36 as shown in Fig. 1 and throwing pawl 46 into engagement 15 with rack 35. Upon movement of the lever 49 in the opposite direction, the reverse action will take place, the spring 51 being compressed, thereby moving pawl 46 out of engagement and pawl 47 into engagement 20 with the corresponding racks.

54 is a boss projecting outwardly from the bracket 25 having pivotally mounted thereupon a lever-arm 55, said lever-arm being slotted at its lower end at 56 for engagement, as herein shown, with a block 57 mounted upon a pin 58 projecting outwardly from the rod 6, movement of said rod 6 through the eccentric strap 5, thus serving to cause a rocking motion of the lever 55 30 about its pivotal support. At 59 and 60 are provided a pair of spaced apart openings in the lever-arm 55, and engagable with either of said openings is a pin 61 forming a pivotal support for the rear end of a link 35 62, said link being pivotally connected at its forward end, as by means of a pin 63, with the lower end of lever-arm 42. While as herein shown the lever 55 is arranged to receive motion from the eccentric 6, it is 40 clearly evident that it is adapted equally well to be actuated from any suitably driven part of the machine.

In producing what is known as a "Baltimore effect" upon the edge of the shoe, it is 45 necessary to gradually increase the width of projection of the forepart of the shoe upon one side thereof to an extent considerably beyond the normal width of the forepart. This effect may be produced in machines 50 as heretofore known either manually as by a gradual further depression of the edge gauge 12 by the operator beyond the point at which it is depressed in forming the remainder of the forepart of the shoe, or in 55 machines so constructed, by the employment of suitably shaped cams acting as pattern devices for gradually depressing the edge gauge at the desired point. The manual operation as described is uncertain and fails 60 to produce uniform results and the machine operation is therefore to be preferred, but as many machines are in use which are unprovided with the mechanical arrangement for producing the desired result, the present invention has been devised whereby existing 65

machines may be provided with mechanism of this character without substantial alteration.

The operation of the mechanism described will now be evident. Bracket 25 having 70 been suitably positioned in the machine, the block 57 engaging within the slot 56 and the cam roll 37 being in engagement with the cam surface 40 of the pattern cam 32, the operator may place the machine in use 75 by depression of the usual starting treadle thereby actuating the presser foot 7 and permitting the proper positioning of the shoe against the relatively fixed edge guide 8, the guide 12 at this time being in its normally raised position, lever 49 being in elevated position, pawl 46 being down but resting on the edge of the cam-carrier beyond the last rack tooth 35 and therefore oscillating idly. The machine operation is 80 started upon the shank portion of the shoe sole, but as the forepart of the shoe is reached, the guide 12 is depressed by means of its treadle through the connections 23, 21, 13 and 16, said edge guide thus projecting 85 below the guide 8, and pushing the upper of the shoe to a greater distance from the cutting blades, producing a greater extension of the sole beyond the upper at this part of the shoe than at the shank portion. It will be noted that in depressing the member 12 as just described, the roll 37 rests upon the rear extremity of the upper surface of the cam-member 32 which forms a fixed support for the rearward end of the 90 lever 15 causing the forward end 17 thereof to partake of the downward movement of the rod 13.

The operation having now reached the point at which it is desired to produce the 105 Baltimore effect, the operator will depress the forward end lever 49 to throw pawl 47 into engagement with the rack 36. As soon as the pawl 47 is in engagement with its rack the rocking movement of the lever 55 110 through the connecting link 62 and the pawl carrying lever 42 will cause the pawl 47 to gradually move the rack 36 rearwardly, carrying therewith the pattern cam 32. As herein shown the pattern cam 32 gradually 115 increases in height from rear to front and by reason of this construction the movement thereof with respect to the roll 37 will produce a gradual lifting of the latter and thereby a gradual depression of the edge 120 guide 12 beyond the lower limit reached by the latter upon depression of the treadle, the position of member 13 and pivot 14 being unaffected by the motion of lever 15, this movement continuing until the pawl 125 has reached the end of the rack-teeth, unless sooner stopped by further manipulation of lever 49 by the operator. As shown in the drawings, the pawl 47 has reached the last tooth of its rack, and the guide 12 has 130

- tion, a bracket-member, a lever, a pair of oppositely directed pawls pivotally mounted upon said lever, a cam-carrier slidable upon said bracket, a pair of racks upon said carrier for engagement by the respective pawls, and manually actuated means comprising a resilient element for throwing said pawls alternately into engagement with the racks. 65
9. In a shoe machine having an edge gauge 10 adjustable manually from and to operative position and provided with a cam operated lever, a detachable bracket-member, a cam-carrier slidable thereon, a cam upon said carrier for engaging said lever, rack elements 15 upon said carrier, vibratory pawls supported upon the bracket for engaging the respective racks, means for actuation from a moving part of the machine for vibrating the pawls, and a manually controllable lever pivoted upon the bracket for selectively determining engagement of the pawls with the respective racks. 20
10. In an attachment for shoe machines, in combination, a bracket-member having a 25 guide channel formed therein, a trough-like cam-carrier slidable in said channel, means for removably positioning a pattern cam-member within said carrier, a pair of racks upon said carrier, a lever pivoted upon said bracket, a pair of oppositely directed pawls pivotally mounted upon said lever for engagement with the respective racks, means for alternately throwing said pawls into and out of engagement with the racks and actuating connections for vibrating said lever. 30
11. In an attachment for shoe machines a reciprocable member having rack - teeth thereon, a vibratory lever having a pawl-carrier pivoted thereto, a pair of oppositely directed pawls fast to said carrier and resilient means for swinging said carrier upon its pivot to thereby throw either of said pawls into engagement with rack-teeth at the will of the operator. 35
12. In an attachment for shoe machines a reciprocable-member having a pair of racks thereon, an adjustable pawl-carrier, means for vibrating said carrier along said racks, a pair of oppositely directed pawls fixed 40 upon said carrier and arranged for alternative engagement with the respective racks, a hand lever, and a coil spring connecting said lever and pawl-carrier whereby movement of said lever resiliently adjusts the pawl-carrier to thereby engage either of said pawls with its corresponding rack at will. 45
13. In a Baltimore attachment, a travelling cam-carrier having a groove therein extending in the direction of travel, and a pattern cam member formed as a flat plate and detachably supported in said groove. 50
14. In a Baltimore attachment, a slidable cam-carrier, and a plate-like member fixedly 55
- carried thereby, said member having one edge thereof formed as a cam. 60
15. In an attachment for shoe machines, a support, a pattern carrier slidable thereon, and a pattern in the form of a substantially flat plate of readily workable material, detachably secured to said carrier. 65
16. In a Baltimore attachment, a movable cam carrier having a channel longitudinal thereof, and a pattern cam member formed as a flat plate and rigidly supported in said channel. 70
17. In a shoe machine, an edge gauge, a pattern-controlled mechanism for adjusting said edge gauge, a slidable support for said mechanism, and means for sliding said support, said means comprising a lever. 75
18. In a shoe machine, an edge gauge, a pattern-controlled mechanism for adjusting said edge gauge, a slidable support for said mechanism and manually operable means for sliding said support. 80
19. In a shoe machine, an edge gauge, a pattern-controlled mechanism for adjusting said edge gauge, and a movable support for said mechanism adapted to move said mechanism to bring said edge gauge from an inoperative position to an operative position, the position of said support being substantially unaffected by the operation of said mechanism. 85
20. In combination with a shoe machine, having a supporting frame and operating elements arranged to operate upon a shoe including a work gauge, of a supplementary mechanism comprising an auxiliary work gauge and position-controlling and actuating means therefor constructed and arranged to be detachably carried by said frame and to be actuated by said operating elements, said mechanism being readily detachable therefrom, and said frame and operating elements remaining in operative relationship during the attachment and detachment of said mechanism. 90
21. In a shoe machine, an edge gauge, means for moving it from and to operative position, and a reciprocating cam for determining said position, said moving means acting at all times unaffected by the position of said cam. 95
22. In a shoe machine, an edge gauge, means for moving said gauge in a path, and mechanism arranged to act while said means is inactive for further moving said gauge in said path. 100
23. In a shoe machine, an edge gauge, means for moving said gauge, and automatic mechanism by which the position of said gauge is varied while said means remains inactive. 105
24. In a shoe machine, an edge gauge, means for moving it from and to operative position, and a cam for adjusting said posi- 110
- 115
- 120
- 125

tion, said moving means having a common position for all operative adjustments of said gauge by said cam.

25. In a shoe machine, an edge gauge, a lever for adjusting the operative position of said gauge, and means for moving said gauge from and to operative position acting on the fulcrum of said lever.

In testimony whereof, he has signed his name to this specification, in the presence of 10 two subscribing witnesses.

FÉLIX EMILE VALOIS.
